UNITED STATES PATENT OFFICE.

CLELL S. KEPLER, OF BLAIRSTOWN, IOWA, ASSIGNOR OF ONE-HALF TO RUDOLPH D. KIMM, OF BLAIRSTOWN, IOWA.

PORTABLE BLOWTORCH ATTACHMENT.

REISSUED

Application filed August 2, 1926. Serial No. 126,731.

This invention relates to a device designed for use in connection with blow torches to facilitate the use of blow torches for heating soldering irons or the like.

5 An important object of the invention is to provide means for supporting irons, while they are being heated by the flame from the blow torch, novel means being provided for dividing the flame of the torch to direct 10 the flame laterally to cause it to contact with the irons supported on opposite sides of the burner.

Another important object of the invention is to provide a device of this character having 15 means for holding the irons prior to the heating thereof, the holding means being constructed to facilitate the handling of the irons.

With the foregoing and other objects in 20 view which will appear as the description proceeds, the invention resides in the combination and arrangement of parts and in the details of construction hereinafter described and claimed, it being understood 25 that changes in the precise embodiment of the invention herein disclosed, may be made within the scope of what is claimed, without departing from the spirit of the invention.

Referring to the drawings: 30 Figure 1 is a vertical sectional view through a device constructed in accordance with the invention.

Figure 2 is a sectional view through the upper portion of the burner housing. 35 Figure 3 is a sectional view taken on line 3-3 of Figure 1.

Figure 4 is a sectional view taken on line 4-4 of Figure 1.

Referring to the drawings in detail, the 40 reference character 5 indicates the base which may be constructed of any suitable material, and to which the lower ends of the supporting members 6 are secured.

The supporting members 6 are substantially 45 inverted U-shaped, the central portion thereof being provided with openings to receive bolts 7 that pass through the bottom 8 of the burner housing 9 to secure the burner housing in position.

50 The bottom of the burner housing is formed with a notch 9' in the front edge thereof to permit the discharge pipe 10 to be moved forwardly so that the upper portion or burner which is indicated at 11 may

be passed into the burner housing 9, without difficulty. 55

The reference character 12 indicates a blow torch which is of the usual and well known construction, and as shown, this blow torch is mounted on the base 5 and held in position by means of the lateral clamps 13 and removable pin 14.

The top of the burner housing is curved as shown by Figure 4 of the drawings, and is provided with lateral openings 15 to admit air to the burner 11 supported therein. At the inner end of the burner housing is a vertical dividing plate 16 that has its forward edge tapered as at 17 to divide the flame passing from the burner 11 to cause 70 it to be directed laterally onto the irons which are supported on the transverse rib 18, forming a part of the housing.

Located at the forward end of the burner housing is a transverse bar 19 provided with 75 a central offset portion 20 of a construction to fit over the inner extremity of the burner, to hold the burner in its proper position.

Disposed at opposite sides of the burner housing and depending therefrom are supporting hooks 21 and 22, which may be employed for supporting the irons used in connection with the device so that the person using the device may have easy access to the irons which may be handled with facility, from their locations on the supporting hooks. 80

It might be further stated that the rib 18 is formed with a central cut out portion 23 provided to act as a rest for the burner 90 when it is positioned within the housing.

In order that the device may be conveniently carried from place to place, a bail 24 is provided. 95

It is thought that in view of the foregoing 95 description a further detail description as to as to the use of the device is unnecessary.

I claim:

A heater including a base, supporting legs on the base, a burner housing secured to the supporting legs, said burner housing having a forward open end and having a plurality of openings formed therein to allow heat to pass therefrom, a transverse bar extending across the burner housing adjacent to the forward end thereof and in spaced relation with the bottom of the housing, said bar having a central offset portion curved to 100 105

receive the burner of a blow torch, a rib within the housing and having a cut out portion disposed centrally thereof and in alignment with the offset portion of the bar to receive the burner and hold the burner against lateral movement, a vertical dividing plate secured to the bottom and having one edge thereof arranged opposite to the

cut out portion to divide the flame from the burner positioned in the housing, and ¹⁰ means for securing a blow torch to the base.

In testimony that I claim the foregoing as my own, I have hereto affixed my signature.

CLELL S. KEPLER.
